(57) **CLAIM**

The ornamental design for a cup lid, as shown and described.

DESCRIPTION

FIG. 1 is a front, top and right side perspective view of a cup lid, showing our new design;

FIG. 2 is a front, bottom and left side perspective view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a left side elevational view thereof;

FIG. 8 is a right side elevational view thereof;

FIG. 9 is a right side elevational cross-sectional view thereof taken in the direction of the cut line indicated 9-9 in FIG. 3; and,

FIG. 10 is a right side elevational cross-sectional view thereof taken on the cut line 10-10 indicated in FIG. 3.

Features of the cup lid that are illustrated by broken lines form no part of the claimed design.

1 Claim, 10 Drawing Sheets
